UNITED STATES PATENT OFFICE.

MICHAEL J. ECONOMIDES, OF BROOKLYN, NEW YORK.

HINGE.

Application filed September 26, 1925. Serial No. 58,795.

This invention relates to an improved concealed hinge which, while being well adapted for general use is, nevertheless, particularly designed to be employed in connection with automobile doors.

The invention seeks, among other objects, to provide a hinge which may be readily fashioned from suitable sheet metal and which, as compared with similar hinges as heretofore constructed, will be more rigid, strong and durable as well as possess superior mechanical features.

The invention seeks, as a further object, to provide a hinge wherein the sides of the hinge box or the fixed hinge member will be rigidly held against spreading so that undue looseness of the movable hinge member with consequent strain and rattling will be avoided.

20 And the invention seeks, as a still further object, to provide a hinge wherein the movable hinge member may, when desired, be readily disengaged from the fixed hinge member for displacing the door.

25 Other objects of the invention not previously specifically mentioned will appear in the course of the following description.

In the accompanying drawings:

Figure 1 is a plan view showing the improved hinge applied with parts of the door and the vehicle body in horizontal section.

Figure 2 is a vertical sectional view on the line 2—2 of Figure 1, looking in the direction indicated by the arrows.

30 Figure 3 is an elevation of the fixed hinge member, the hinge arm of the movable member being broken off.

Figure 4 is a section on the line 4—4 of Figure 1, looking in the direction indicated by the arrows.

Figure 5 is a plan view of the blank from which the fixed hinge member is formed.

Figure 6 is a detail perspective view of the reinforcing plate for the fixed hinge member.

Figure 7 is a detail perspective view of the movable hinge member.

Figure 8 is a view similar to Figure 1 showing a slightly modified form of the invention applied.

Figure 9 is a vertical sectional view of the structure shown in Figure 8.

Figure 10 is a plan view of the blank from which the fixed hinge member of the modified structure is formed.

Figure 11 is a view similar to Figures 1 and 8 showing a further modified structure.

Figure 12 is a detail perspective view of the fixed hinge and associated parts of the structure shown in Figure 11.

Figure 13 is a plan view of the blank from which the fixed hinge member of Figure 12 is formed.

Figure 14 is a sectional plan view showing still another modification of the invention.

Figure 15 is a section on the line 15—15 of Figure 14, looking in the direction indicated by the arrows.

Figure 16 is a section on the line 16—16 of Figure 14, looking in the direction indicated by the arrows.

Figure 17 is a plan view of the blank from which is formed the fixed hinge member shown in Figure 14.

Figure 18 is a fragmentary perspective view showing the anchoring tongue of the latter modified structure.

Referring now more particularly to Figures 1 to 7 inclusive, the numeral 10 indicates a portion of a vehicle body and the numeral 11 a portion of a door. Countersunk in the body 10 is the fixed hinge member employed. This member is, as shown in Figure 5, initially struck from suitable resilient sheet metal in the form of a blank 12, which is bent along the dotted lines illustrated, to provide a rectangular box 14 from the top and bottom of which project oppositely directed face plates 15. These face plates are countersunk in the adjacent edge of the body 10 and are apertured to receive screws 16 securing the hinge member in position while, as particularly shown in Figures 1, 2 and 4, the door frame or body 10 is provided with a recess 17 to accommodate the box 14.

The box 14 is provided with parallel top and bottom walls 18 and 19 and a back wall 20, but is open at its ends and at the front thereof. Formed in the bottom wall near one of its rear corners is an opening 21 above which the top wall 18 is cut away, as indicated at 22, while at the outer end of said cut away portion, the upper face plate 15 is, as particularly seen in Figure 3, provided with a notch 23. As brought out in Figures 2 and 4, the recess 17 is provided in its upper wall with a cavity 24 which extends substantially flush with the upper edge of the notch 23 over the cut away por-

tion 22 of the top wall of the box. Formed on the top wall of the box 14 near one of its forward corners is a downturned lug 25, best seen in Figure 4, and formed on the bottom 5 wall of said box to overlie the lug 25 is an upturned lug 26 having a tongue 27 which, as shown in Figure 3, is bent across the forward edge of the lug 25 to extend a short distance longitudinally within the adjacent 10 end of the open front of the box. Extending through the lugs 25 and 26 is a rivet 28 rigidly securing said lugs together. Formed on the bottom wall 19 of the box at its opposite forward corner is an upturned angular 15 lug 29, and formed on the upper face plate 15 to extend across the adjacent end of the open front of the box is an extension 30 overlying the front flange of the lug 29. The extension 30 is provided with a rearwardly directed lug 31 which, as best seen 20 in Figures 1 and 4, overlies the side flange of the lug 29, and extending through said lug and flange is a rivet 32 rigidly securing the lugs together. Thus, as will be seen, 25 the top and bottom walls 18 and 19 of the box 14 are rigidly united at one end of the box by the pair of lugs 25 and 26 while the upper face plate 15 is connected with the bottom wall of the box and with the lower 30 face plate at the opposite end of the box by the pair of lugs 29 and 31. Spreading of the top and bottom walls of the box will thus be effectually prevented.

In conjunction with the fixed hinge member, I provide an angular reinforcing plate 33. This plate is of suitable resilient sheet metal and, as shown in Figure 2, is shaped to fit in the angle between the bottom wall 19 of the box 14 and the lower face plate 40 15 and is welded or otherwise integrally connected therewith. The plate 33 is, as shown, provided with openings to accommodate the lower securing screws 16 as well as with an opening 34 to register with the opening 21 45 of the wall 19. However, the use of the reinforcing plate is optional, depending upon whether or not the plate is thought to be necessary for any particular installation.

The movable member of the hinge, like 50 the fixed member, is constructed of suitable resilient sheet metal and, as shown in Figure 7, is formed of companion sections embodying plate portions abutting at their inner longitudinal edges to form a base plate 55 35. Projecting from said edges of the plate portions are overlapping registering portions of a laterally directed substantially L-shaped arm 36. The portions of said arm are welded together or otherwise integrally 60 united for rigidly connecting the sections of the member with each other, and extending through the arm near its free end is a depending pivot pin 37 preferably welded to the arm. The base plate 35 is countersunk 65 in the adjacent edge of the door and is aper-

tured to receive screws 38 connecting the hinge member with the door, while the arm 36 projects into the box 14 of the fixed hinge member and is pivotally connected therewith by the pin 37 which fits through the 70 registering openings 21 and 34 of the wall 19 of the box and the plate 33 respectively. Thus, the door is mounted for free swinging movement and when swung open, the arm 75 36 travels to the position shown in Figure 1, while when the door is closed, said arm is received within the box 14 and, in this connection, attention is directed to the fact that the arm is of a thickness to quite snugly fit between the top and bottom walls 18 and 80 19 of the box so that these walls will coact with the arm to prevent rattling.

After the door has been swung open, it may be lifted for shifting the inner end of the arm 36 upwardly into the cavity 24 of 85 the recess 17 of the door frame or body and the notch 23 of the upper face plate 15, as shown in dotted lines in Figure 2, the pivot pin 37 being thereby elevated to clear the opening 21 in the bottom wall 19 of the box 90 14. The arm may then, of course, be withdrawn forwardly from the box through the notch 23 to free the door. Thus, the door may, when desired, be readily detached. Reverse movements facilitate and effect assembling of the hinge members. 95

In Figures 8, 9 and 10 of the drawings, I have illustrated a slight modification of the invention in connection with a portion of a vehicle body 39 and a portion of a door 40. 100 Fixed and movable hinge members of suitable resilient sheet metal are employed as in the previously described embodiment of the invention. The fixed hinge member is struck from a blank 41 which is bent along the dotted lines shown to provide a box 42 from which project upper and lower face plates 43. The box is countersunk in the body 39, which is provided with a cavity 44 to accommodate the box, and extending through the face plates 43 are screws 45 securing the hinge member in position. The box 42 is provided with parallel top and bottom walls 46 and 47, the former of which is cut away as indicated at 48 while the latter is provided 115 near one of its rear corners with an opening 49. At 50 I have shown a reinforcing plate like the plate 33, the plate 50 being intended to serve a similar function. However, said plate may or may not be employed as found expedient, but, in use, is preferably welded in position. Formed in the face plate 43 is a notch 51 while the recess 44 is provided in its top with a cavity 52 extending in the rear of said notch. Formed on the bottom wall 120 47 of the box 42 at its outer forward corner is an upturned angle lug 53 and formed on the upper face plate 43 to overlie the front flange of said lug is an extension 54. Projecting from said extension is a rearwardly 125 130

turned lug 55 which overlies the side flange of the lug 53, and said lugs are welded together, the extension 54 being secured to the lug 53 in like manner. Thus, the upper face plate 43 is rigidly connected, at the adjacent end of the box 42, with the lower face plate, so that the top and bottom walls 46 and 47 of the box 42 will be rigidly held against spreading movement.

10 The movable hinge member employed in this modified structure is identical with the movable hinge member previously described and includes a base plate 56 which is screwed to the door 40, and projecting from said plate is an arm 57 which extends into the box 42 of the fixed hinge member and carries a pin 58 which fits through the opening 49 in the bottom wall of said box and through a like opening in the reinforcing plate 50. The parts are thus pivotally connected by said pin while, by lifting the door, the pin may be freed and the arm withdrawn through the notch 51 for detaching the door. As in the prior structure, the arm 57 is of a 25 thickness to be quite snugly received between the top and bottom walls of the box 42 so that undue looseness and rattling will be prevented.

In Figures 11, 12 and 13 of the drawings, 30 I have illustrated a further modification of the invention, a portion of a body being indicated at 59, and a portion of a door at 60. Fixed and movable hinge members of suitable resilient sheet metal are employed as in 35 the previously described structures. The fixed hinge member is struck from a blank 61, which is bent along the dotted lines illustrated to provide a box 62 having top and bottom walls 63 and 64 from which project

40 oppositely directed face plates 65 and 66. These plates are apertured to receive screws securing the hinge member to the door frame and the frame is recessed to accommodate said members as before described. The top 45 wall 63 of the box is cut away as indicated at 67, while the bottom wall is provided with an opening 68, and formed in the upper face plate 65 opposite said opening is a notch 69. As particularly shown in Figure 12, the 50 lower face plate 66 is provided at the end edges of the bottom wall 64 of the box with substantially V-shaped notches 70 and formed on the upper face plate 65 at the side edges thereof are depending tongues or lugs 55 71 having inclined ends fitting in said notches. The tongues are welded in the notches so that the face plates 65 and 66 are thus rigidly connected with each other while the top and bottom walls 63 and 64 of the 60 box 62 are rigidly braced against spreading.

In conjunction with the fixed hinge member, I have shown a reinforcing back plate 72 which is of suitable resilient sheet metal and is apertured to fit over the box 62 of said member so that the reinforcing plate

may thus lie flat, as shown in Figure 11, against the rear sides of the face plates 65 and 66. The reinforcing plate 72 is welded to the face plates and the aperture in the reinforcing plate is extended upwardly at one 70 end, as particularly seen in Figure 12, so that the reinforcing plate will clear the notch 69 of the upper face plate 65. Projecting rearwardly from the lower edge of the opening in the reinforcing plate is a 75 tongue 73 which lies flat against the bottom wall 64 of the box 62 and is welded to said bottom wall. The tongue will thus reinforce the box and is provided with an opening 74 to register with the opening 68 in said bottom wall.

I have further illustrated a reinforcing front plate 75 for the fixed hinge member. This plate is welded flat against the front faces of the face plates 65 and 66 and is 80 provided with a substantially L-shaped opening 76 to register with the open front of the box 62 and with the notch 69. The plates 72 and 75 will thus rigidly reinforce the fixed hinge member and, as shown, said plates are provided with apertures to register with the apertures in the face plates 65 and 66 so that the securing screws for the fixed hinge member may extend through all of said plates, the plates being, as shown 95 in Figure 11, countersunk in the body 59.

Attention is directed to the fact that the fixed hinge member may, if desired, be employed without the plates 72 and 75 but, to meet the requirements of practical installation, said plates are provided in order that either one or both of the plates may be used to reinforce the fixed hinge member, as may be considered expedient.

The movable hinge member is identical 105 with the movable member first described and includes a face plate 77 which is screwed to the door 60, and projecting from said face plate is an arm 78 carrying a pin 79 which fits through the opening 68 of the 110 bottom wall 64 of the box 62 and through the opening 74 of the tongue 73 for swingingly supporting the door. The arm 78 is of a thickness to be more or less snugly received between the top and bottom walls 115 63 and 64 of the box so that rattling will be prevented while, by lifting the door, the arm may be raised for freeing the pivot pin 79, in the manner previously described, to detach the door.

120 In Figures 14, 15, 16, 17 and 18, I have illustrated still another form of the invention, a portion of a body or frame being indicated at 80 and a portion of a door at 81. The fixed hinge member is struck from a 125 blank 82, which blank is bent along the dotted lines illustrated to provide a box 83 having top and bottom walls 84 and 85 from which project oppositely directed upper and lower face plates 86 and 87 re- 130

spectively. These face plates are, as shown in Figure 16, countersunk in the body 80 and are apertured to receive screws 88 which secure the hinge member in position while the body is provided with a recess 89 to accommodate the box 83. Formed on the upper face plate 86 at one side edge thereof, as shown in Figure 18, is a tongue 90 which is offset to extend in the rear of the face plate 87 at one end of the box, and this tongue is welded to the latter face plate for rigidly connecting the face plates with each other. Formed on the bottom wall 85 of the box, at the opposite end thereof, is an upward turned lug 91, and formed on the adjacent end of the top wall 84 of the box is a down-turned lug 92. The lug 92 is angle shaped. One flange thereof overlies the lug 91 while the other flange projects a short distance within the adjacent end of the open front of the box. The lugs 91 and 92 are welded together for rigidly connecting the face plates 86 and 87 with each other at the adjacent end of the box so that these lugs, in conjunction with the tongue 90, will serve to rigidly hold the top and bottom walls of the box against spreading movement. At one end, the top wall 84 of the box is reduced and the adjacent margin of said wall is bent to form a flange 93 extending between the back wall of the box and the face plate 86 and projecting downwardly toward the bottom wall 85 of the box. Near its opposite end, the top wall is further provided with a keyhole slot 94 which, as shown in Figure 16, opens through the face plate 86, while, at its rear end, said slot is provided with a circular portion 95.

The movable hinge member is similar to the movable hinge member first described and includes a face plate 96 which is countersunk in the door 81 and is secured thereto by screws 97. The hinge member is formed of sections, and projecting from the plate portions of said sections are the overlapping portions of an arm 98, the portions of the arm being welded together. Extending through the free end of the arm is a pivot pin 99 which projects above and below the arm and is welded thereto. Immediately above the arm, the pin is provided with an annular groove 100, and in order to permit the removal of the pin from the keyhole slot 94, the recess 89 in the body 80 is provided above said slot, as seen in Figure 16, with a cavity 101.

As will now be seen, the arm 98 of the movable hinge member is freely received within the box 83 of the fixed hinge member and the upper end of the pin 99 fits in the circular portion 95 of the keyhole slot 94 while the lower end of said pin fits in an aligned opening 102 in the bottom wall 85 of said box for pivotally connecting the movable hinge member with the fixed member.

Accordingly, the door is supported for free swinging movement and, in this connection, it is to be observed that the pivot pin 99 is journaled at both ends while, when the door is closed, the arm 98 is, as shown in Figure 15, snugly received between the bottom wall 85 of the box 83 and the flange 93 of the top wall 84 of said box so that the arm is thus limited against movement and rattling is prevented. To detach the door, said door is lifted until the lower end of the pin 99 is elevated out of the opening 102 in the bottom wall of the box when the groove 100 in the upper end of the pin will lie within the circular portion of the keyhole slot 94 while the upper terminal of the pin will be accommodated in the cavity 101. The groove 100 defines a reduced neck on the pin which is adapted to freely pass forwardly through the keyhole slot 94 so that after the door has been lifted, as indicated, the door may be manipulated for withdrawing the arm 98 and pin 99 out of the box 83. Thus, the door may be readily removed when so desired.

In this modification, I have also shown the use of a reinforcing plate 103 which is identical with the plate 33 and serves a like purpose. However, it is to be understood that the plate 103 may, or may not, be employed, as occasion may demand. In any instance where the plate is used, this plate is preferably welded to the bottom wall 85 of the box 83 and to the lower face plate 87 and is provided with openings to accommodate the securing screws which extend through said lower face plate, as well as with an opening 104 to receive and journal the lower end of the pin 99.

Having thus described the invention, what I claim is:

1. In a hinge, a hinge member formed of a sheet metal blank having lugs and bent to define a box open at the front thereof and provided with top and bottom walls, said lugs being bent into overlapping relation on a side of the box at the front corner thereof and being secured together for rigidly limiting said walls against spreading movement at the open front of the box.

2. In a hinge, a hinge member formed of a sheet metal blank bent to define a box open at the front thereof and provided with top and bottom walls having face plates extending therefrom, one of said plates being provided with a portion extending across the open front of the box and around the adjacent corner thereof and the opposed wall of the box being provided at its side with a lug rigidly secured to said portion for rigidly bracing the box against distortion at the open front thereof.

3. In a hinge, a hinge member formed of a sheet metal blank bent to define a box open at the front thereof and provided with top

and bottom walls having face plates extending therefrom, said bottom wall being provided with upstanding lugs on its sides at its front corners and said top wall and one of said face plates being provided with lugs overlapping said first mentioned lugs, and fastening devices rigidly securing said lugs together for bracing the box against distortion at the open front thereof.

10 4. In a hinge, a hinge member formed of a sheet metal blank bent to define a box open at the front thereof and provided with top and bottom walls having face plates extend-

ing therefrom, said bottom wall being provided with upstanding lugs on its sides at 15 its front corners and said top wall and one of said face plates being provided with lugs overlapping said first mentioned lugs, and means rigidly securing said lugs together for bracing the box against distortion at the 20 open front thereof, the lugs at one corner of the box being of angular formation to extend around the corner and across the open front of the box.

In testimony whereof I affix my signature.
MICHAEL J. ECONOMIDES. [L. s.]
